DESIGN FOR A CHRISTMAS ORNAMENT

Theodore L. Gehr, St. Petersburg, Fla.

Application October 15, 1947, Serial No. 141,904

Term of patent 3½ years

(Cl. D29—1)

To all whom it may concern:

Be it known that I, Theodore L. Gehr, a citizen of the United States, residing at St. Petersburg, in the county of Pinellas and State of Florida, have invented a new, original, and ornamental Design for a Christmas Ornament, of which the following is a specification, reference being had to the accompanying drawing, forming part thereof.

Fig. 1 is a front perspective view of a Christmas ornament, showing my new design.

Fig. 2 is a similar view looking from the rear.

I claim:

The ornamental design for a Christmas ornament, as shown.

THEODORE L. GEHR.
